(57) **CLAIM**

The ornamental design of a shoe, as shown and described.

DESCRIPTION

FIG. 1 is a medial top perspective view of a shoe;
FIG. 2 is a medial bottom perspective view thereof;
FIG. 3 is a lateral top perspective view thereof;
FIG. 4 is a lateral bottom perspective view thereof;
FIG. 5 is a medial side view thereof;
FIG. 6 is a back view thereof;
FIG. 7 is a lateral side view thereof; and,
FIG. 8 is a top view thereof.

The broken lines showing the remainder of the shoe are for environmental purposes only, and form no part of the claimed design.

1 Claim, 8 Drawing Sheets
